UNITED STATES PATENT OFFICE

120,685

DESIGN FOR A SHOVEL BUCKET

Courtney W. Kimler, Sr., Ames, Iowa

Application December 11, 1939, Serial No. 88,832

Term of patent 14 years

To all whom it may concern:

Be it known that I, Courtney W. Kimler, Sr., a citizen of the United States and a resident of Ames, in the county of Story and State of Iowa, have invented a new, original, and ornamental Design for a Shovel Bucket, of which the following is a specification, reference being had to the accompanying drawing forming part thereof.

I claim:

The ornamental design for a shovel bucket, substantially as shown.

COURTNEY W. KIMLER, SR.
